ROBERT L. GIBSON, OF PHILADELPHIA, PENNSYLVANIA.

STYLUS.

1,260,365.

Specification of Letters Patent. Patented Mar. 26, 1918.

Application filed December 29, 1913. Serial No. 809,186.

To all whom it may concern:

Be it known that I, ROBERT L. GIBSON, a citizen of the United States, and resident of the city and county of Philadelphia and State of Pennsylvania, have invented an Improvement in Styli, of which the following is a specification.

The present invention relates to a stylus for sound recording machines adapted to produce a sound record or phonogram in the form of a raised ridge or rib which may be used as a mold (directly or indirectly) to form on a plate or disk of suitable material a complementary groove adapted for 15 the reproduction of sound in the usual sound reproducing machines.

The stylus is particularly adapted for use in connection with the apparatus shown in my application 809,188, filed December 29th, 20 1913, for carrying out the process described in my application 809,187, filed December 29th, 1913.

The stylus consists of a hollow tube having a vibratory portion adapted to vibrate 25 under the impulse of sound waves and terminating in a very small orifice. When the stylus is used for the process of application 809,187, above referred to, the orifice is of microscopic size, smaller than a capillary 30 duct, so that the material ejected through it is an extremely fine thread or stream much smaller in cross section than the ridge or rib which is formed, the latter being produced by the building up of the material 35 upon itself by ejecting the fluid through the stylus much more rapidly than the surface upon which it is deposited moves. When it is understood that in practice the finished phonautographic ridge is preferably only 40 .005 of an inch in width and .0025 of an inch in height and that the stream ejected through the stylus has a cross section much less than such a ridge, the microscopic dimensions of the orifice will be appreciated.

Owing to the minuteness of the orifice it is necessary that the material which is ejected through it should be thoroughly strained as even the most minute particle of solid matter would clog the orifice and render the stylus inoperative. To obviate this 45 I provide the stylus with filtering material and as the material is forced through the stylus under very great pressure this filtering material is very highly compressed.

I have found that a stylus suitable to the 55 purpose can best be formed of glass which can be drawn to a fine vibratory end terminating in an orifice of microscopic dimensions while the upper part may be left sufficiently large to contain the filtering mate- 60 rial, and I prefer that construction.

The invention also embraces the combination with the stylus proper of the nipple or means to which it is secured and by which it may be attached to the machine.

Further objects and advantages are set forth hereinafter when referring to the accompanying drawings, in which Figure 1 is an enlarged vertical section of the stylus and its support showing the preferred construction; Fig. 2 is a side elevation with parts in section showing the stylus attached to the apparatus in which the record making material is contained and connected with a recording sound box; Fig. 3 is a top view of 75 the stylus; and Fig. 4 is a detail view showing a modified form of the means for bracing the vibratory portion of the stylus.

The hollow stylus *a* is provided with a fine tubular vibratory portion *e* operated by the 80 impulses transmitted to it by the vibrations imparted by sound waves to the diaphragm of a recording instrument *b*.

The stylus is preferably made of a blown and drawn glass tube shaped in the form 85 shown in Fig. 1, comprising an enlarged chamber or bulbous portion *c* at the top partially closed by the inwardly directed flange *c'*, an intermediate portion *d* with substantially parallel sides *d'*, and a fine 90 vibratory portion *e* gradually tapering and containing an axial bore *e'* of decreasing diameter terminating in the orifice *e''*. To protect this slender portion *e* as much as possible and to prevent it from vibrating in 95 any plane other than that in which it is moved by the impulses from the sound box, I find it of advantage to employ a brace *f* preferably made of an angular tapered piece of glass welded at its larger end *d''* to the 100 sides *d'* of the portion *d* and at its smaller end *d'''* near the point of the fine vibratory portion *e*.

A support or thimble *g* for the stylus is 105 preferably shaped substantially as shown in Fig. 1 and comprises a metal cylindrical portion *g'* preferably made of steel and provided with internal threads *g''* and partially

closed at its lower end by an inwardly directed flange g^3 , having a central opening slightly larger than the outside diameter of the portion d of the stylus. Fitting closely about said section l are one or more washers h , preferably of asbestos, and above the washers is a ferrule h' , preferably of lead or other relatively soft metal, or metal alloy, apertured to receive and support the stylus while its periphery is threaded for engagement with the threads g^2 , whereby the ferrule is screwed down to firmly secure the washers h in place.

The stylus is filled with any suitable filtering material i , such as cotton or other fibrous substance, under suitable compression, and this is held in the stylus and the stylus in place by porous washers i' of felt or the like, which in turn are firmly pressed downwardly by a cap j provided with a central aperture j' . The cap is forced downward by a spring k tensioned by a plug l recessed at l' and screwed into the top of the thimble g . The plug l is provided with a central aperture l^2 , which connects with the passage m leading from a source of supply (not shown) of the record making material. The thimble g is removably secured to the supporting head or plate by a coupling n having a central aperture and embracing the flange g^4 on the upper edge of said thimble.

To protect said coupling and thimble, a substantially cylindrical shield o is provided, which is secured to the supporting head or plate with which the thimble is coupled. To surround and directly protect said stylus, an inverted conical shield p is secured to the outside of the shield o and this is provided with a central aperture p' through which the stylus extends, while a second aperture p^2 in one side permits a direct connection between the stylus and the diaphragm of the recording instrument b , said connection extending in a plane at right angles to the plane of the brace f .

While the invention is not limited to the process of forming and applying the stylus, I consider the following to be the simplest and most convenient manner of carrying out the same: The glass tube is first blown to produce the bulbous end e ; after the tube is filled with the cotton or other filtering material i , it is introduced into the thimble g with the shank projecting through the ferrule h' and washers h . The spring k with the plug l , cap j and the washers i' are then applied and the plug l is screwed down to fasten the glass tube securely in place. The lower end of the tube is then heated and drawn to form the fine vibratory portion e . As the pressure at the top is applied through the cap j and the washers i' , and the contact of the shank at the swelling of the bulbous end is with the soft lead ferrule h' ,

the tube may be firmly secured without fracture, and when it is thus secured, the lower end e may be drawn in the manner described to an exceedingly fine point.

A modified form of support and guide for the vibratory portion of the stylus is shown in Fig. 4, in which the brace f is omitted and in place thereof is provided a wire or filament r , surrounding said stylus and extending in opposite directions through the shield p and secured at its ends to angular braces s upon the outside of the shield.

As this invention relates only to the stylus and its support, it is unnecessary to describe either the recording device, or disk actuating mechanism, or that portion of the apparatus, with which the stylus is especially adapted to be employed which contains the record making material or forces the same through the stylus.

While a preferred form of the device has been described, the invention is not limited to the exact details shown, it being possible to make many changes in the device while still embodying all of the essential features or elements characteristic of the invention.

What I claim is as follows:

1. A stylus for a sound recording machine composed of a glass tube drawn to an exceedingly fine point presenting a microscopic discharge orifice.

2. A stylus for a sound recording machine having a microscopic discharge orifice and adapted to eject, under pressure, a readily solidifying fluid material, said orifice being of a diameter much less than .005 inch and therefore adapted, when vibrated under the influence of sound waves and properly disposed relatively to a surface traveling at a substantially slower speed than the speed of ejection of said material, to build upon said surface a sound record in distinct relief and of a width substantially greater than the diameter of said discharge orifice.

3. A stylus for a sound recording machine consisting of a tube having a capillary bore terminating in a microscopic discharge orifice of substantially less diameter than the average diameter of the capillary bore.

4. A stylus for a sound recording machine consisting of a tube having a capillary bore of very gradual taper and terminating in a microscopic discharge orifice.

5. A stylus for a sound recording machine consisting of an integral tubular body having a plurality of decreasing cross-sectional areas, the smallest of which has a capillary bore terminating in a microscopic discharge orifice.

6. A stylus for a sound recording machine consisting of an integral tubular body having a plurality of decreasing cross-sectional areas, the smallest of which has a capillary bore of very gradual taper terminating in a microscopic discharge orifice.

7. A stylus for a sound recording machine consisting of a hollow tube and a thimble inclosing the upper end of the tube having an orifice inclosing the tube between its upper and lower end portions. 5
8. A stylus provided with an enlarged bulbous portion leading through an intermediate section into a tapering bore having a microscopic outlet. 10
9. A stylus provided with an enlarged bulbous portion leading, through an intermediate and smaller section with substantially parallel sides, into a tapering bore having a microscopic outlet. 15
10. A stylus provided with an enlarged bulbous portion leading through an intermediate section into a tapering bore having a microscopic outlet, said bulbous and intermediate sections being provided with filtering material. 20
11. A stylus comprising an integral structure provided with a bulbous portion containing filtering material, and terminating in a bore having a microscopic outlet. 25
12. The combination of a hollow tapering stylus, a thimble having an outlet through which said stylus extends, and cushion means operative to support said stylus out of contact with said thimble. 30
13. The combination of a hollow tapering stylus, a thimble having an outlet through which said stylus extends, adjustable means to detachably secure said stylus in said thimble, and cushion means operative to support said stylus out of contact with said thimble and adjustable securing means. 35
14. The combination of a hollow tapering stylus provided with filtering material, a thimble having an outlet through which said stylus extends, means to secure said stylus in said thimble, cushion means operative to support said stylus out of contact with said thimble, and filtering means between said stylus and said means for securing it in the 40 thimble. 45
15. A vibratory stylus provided with a capillary bore and means to brace said stylus against vibration in one direction. 50
16. A vibratory stylus provided with a capillary bore and means to brace said stylus against vibration in one direction consisting
- of a brace-piece extending from the shank of the stylus to the point. 55
17. A stylus composed of glass having a capillary bore and drawn to a fine point, and means to brace said stylus against vibration in one direction consisting of a glass brace piece extending from the shank of the stylus to the point. 60
18. A stylus for a sound recording machine formed of an integral body having at its upper end a relatively large chamber open above and below and the lower part continuing in a relatively small and gradually tapering bore terminating in a microscopic orifice, the large chamber filled with a tightly fitting filtering material. 65
19. A stylus for a sound recording machine consisting of a hollow vibratory tube having an enlarged hollow portion at one end and a long tapered portion terminating in a microscopic orifice at the other end, and compressed filtering material in the enlarged hollow portion. 70
20. A stylus for a sound recording machine consisting of a hollow vibratory tube terminating in a microscopic orifice and having an enlarged bulbous portion at the top containing a filtering material. 75
21. A stylus for a sound recording machine consisting of a hollow vibratory tube enlarged at the top and having a capillary bore terminating in a microscopic orifice and containing compressed filtering material in said enlargement and capillary bore. 80
22. A stylus for a sound recording machine consisting of an integral body in the form of a tube in which the portion adjacent to one end is of large diameter and relatively non-vibrating and the portion adjacent to the other end is of small diameter terminating in a microscopic orifice and capable of freely vibrating, combined with means for supporting the portion of large diameter and means for vibrating the portion of small diameter having the microscopic orifice. 85

In testimony of which invention I hereunto set my hand.
